UNITED STATES PATENT OFFICE

148,848

DESIGN FOR A SCOOTER

Zvi Gezari, New York, N. Y.

Application October 19, 1946, Serial No. 134,082

Term of patent 7 years

(Cl. D34—15)

To all whom it may concern:

Be it known that I, Zvi Gezari, a citizen of the United States, residing at New York city, in the county of New York and State of New York, have invented a new, original, and ornamental Design for a Scooter, of which the following is a specification, reference being had to the accompanying drawing, forming part thereof.

The drawing shows a perspective view of a scooter, showing my new design.

The dominant features of my design reside in the portions shown in full lines.

I claim:

The ornamental design for a scooter, substantially as shown and described.

ZVI GEZARI.
